MONOTYPE MACHINE COMPANY, OF PHILADELPHIA, PENNSYLVANIA, A CORPO-
RATION OF VIRGINIA.

SEMITIC TYPE-CASTING MACHINE.

1,356,450.

Specification of Letters Patent.

Patented Oct. 19, 1920.

Application filed January 31, 1920. Serial No. 355,519.

To all whom it may concern:

Be it known that I, MAURITZ C. INDAHL, a citizen of the United States, residing at Philadelphia, county of Philadelphia, State 5 of Pennsylvania, have invented certain new and useful Improvements in Semitic Type-Casting Machines; and I do hereby declare the following to be a full, clear, and exact description of the same, reference being had 10 to the accompanying drawings, forming a part of this specification, and to the characters of reference marked thereon.

This invention relates to machines for casting and composing single types in justified lines which after being formed are pushed into a galley to form a column. More particularly the invention relates to machines in which the type and lines produced are reversed as in Semitic or like languages 20 in which reading matter differs from English in that the lines are read from right to left. A machine adapted for English composition may be used for Semitic composition provided the Semitic matrices are reversed or turned through 180° with respect to the position of the English matrices and provided also that the composed lines are delivered in the galley in a direction opposite to that of delivery for type lines in the 25 English language. In either case, it may be noted, the delivery is in the same direction with respect to the position of the characters on the type bodies: for example, it may in each case be toward the foot or bottom of 30 the characters.

The main object of the invention is to provide a typographic machine for reversed composition, such as Semitic, the construction of which shall be free from mechanical 40 complications and the operation of which is safe and sure without producing strains beyond what the machine as a whole or the various parts thereof are designed properly to withstand. Another object is to provide, 45 in a machine for casting types in selected sequence and conveying them in the form of a line to a line channel, lifter mechanism embodying a platform and a wall to support both the foot and one of the sides of 50 each type while the line is raised to position for discharge to a level other than that

of the said line channel. These objects and others which will appear hereinafter will be further explained and made clear in connection with the following description of an 55 embodiment of the invention shown in the accompanying drawings in which

Figure 1 is a plan view including certain parts of a type casting and composing machine in which the invention is shown embodied.

Fig. 2 is a side elevation thereof.

Fig. 3 is a sectional elevation on substantially the line 3—3 of Fig. 1, but showing 65 the type line platform and the line gate or rule in elevated position.

Fig. 4 is a sectional view of a portion of the mechanism of Fig. 3 showing the operation of the platform lifting connection 70 when the platform is by accident prevented from lifting.

Fig. 5 is a perspective view of the galley mechanism of the invention.

For illustrative purposes it has been 75 chosen to show the invention as embodied in a single type casting and composing machine which is well known as manufactured and sold by Lanston Monotype Machine Company and the general organization of 80 which is set forth in United States Patent No. 625998, dated May 30, 1899. Such a machine is adapted for composition in English and like languages: The present invention contemplates alterations and 85 changes therein to adapt it for Semitic composition and such changes are located—except for the reversing of the matrices previously referred to—wholly in the galley mechanism, that is, the galley itself and the 90 mechanism associated therewith including that for moving the composed line into the galley. The construction and functioning of the mechanisms in such machine for selecting and positioning the matrix, dimensioning the mold, casting the type and ejecting 95 it into the line channel as well as the other mechanisms associated with such operations are unchanged; and for that reason and for the reason that the machine is well 100 understood by those skilled in the art, it is deemed unnecessary to illustrate and describe the entire machine. Certain parts

of the machine, particularly those which perform functions immediately before the delivery of the line into the galley, are shown in the drawings, however, and of them it 5 may be of assistance to mention the following to clearly identify the machine: the paper tower A for the paper strip controller having signal perforations to govern the matrix positioning devices B, B', by which 10 a selected matrix is positioned over the mold C provided with the cross block D and the dimensioning and ejecting blade E; the molten metal pot F provided with the pump mechanism G; the type carrier H; the line 15 channel I, the line hook K and its operating mechanism including the lever L and cam disk M; the main galley frame or stand N; the fixed channel block O. As is well known these various mechanisms as well 20 as other mechanisms of the machine, not shown, operate in properly timing relation to select and position a desired matrix, lower it over the mold properly dimensioned, inject molten type metal into the 25 mold against the matrix, and eject the type thus formed from the mold and deliver it into the line channel I; also, when a line of type has been so delivered, the cam M is operated to cause the line hook K and its operating 30 mechanism L to draw the line to a position in which it may be pushed laterally into the galley. These mechanisms and their operation being well understood by those skilled in the art require no further 35 description here.

As has been hereinbefore stated, the machine above referred to is adapted for English language composition and the line of type in front of the galley is pushed toward 40 the right of the machine, but for Semitic composition the galley is required to be located at the left of the machine and the line must be pushed therefore to the left as shown in Fig. 1. The galley 1, according 45 to the present invention is located at the left of the line channel I above the galley mechanism operating cam disk M and above the level of the line channel. The type line must therefore be raised from the channel level to 50 the galley level and this is accomplished by the provision of a pivoted type line lifter mechanism comprising the frame 2 pivoted at one end on the shaft 3 supported on the bracket 4 secured by bolts 5 to the cross bar 55 6, the latter being provided in its upper surface with a dove tailed groove with the walls of which the beveled heads of the bolts 5 coöperate whereby upon loosening the bolt nuts the bracket 4 and the type line lifter 60 may be adjusted in a direction parallel with the line channel I. The crossbar 6 is itself supported on the rods 7 extending from the main supporting bracket 8 secured to the main galley frame or stand N. The cross 65 bar 6 is adjustably secured to the rods 7 by

the wing set screws 9 by the manipulation of which, it is obvious, the type line lifter may be adjusted in a direction at right angles to the line channel I. The rods 7 are likewise adjustable with respect to the supporting bracket 8 by manipulation of the wing set screws 10. The said bracket is provided with a raised portion 11, the upper surface of which is substantially on a level with that of the cross bar 6 and is likewise provided with a dove-tailed groove for co-operation with a bevel bolt 12 for adjustably securing to the portion 11 the wiper plate 13, more particularly described hereinafter. It may be noted that the parts 6, 7, 8, 9, 10, 11 and 12 are all standard parts of the present commercial machine based upon the machine of the above mentioned patent.

The type line lifter frame 2 comprises parallel side bars connected together by the cross piece 14 near the shaft 3, and the channel member 15 at the end of the frame opposite to the end pivoted on shaft 3, said member 15 being provided with a column pusher recess 16 and with a type line platform 17 (Fig. 3) for receiving a line of types delivered along the type channel I by the line hook K. In the normal or lowered position of the lifter frame 2 the platform 17 rests upon the type channel plate 18, which is recessed to accommodate the platform 17 so that normally the upper horizontal surfaces of the platform and the plate are on the same level. The type feet resting on the upper surface of the plate are caused to slide 100 along the channel by the action of the line hook during which motion the feet leave the plate and are transferred to the lifter platform. The plate 18 is secured to the main galley bracket or stand N and the platform 17 may be a separate plate secured in a suitable manner to the underside of the channel member 15 and projecting beyond said member sufficiently to receive the feet of the type.

In the recess 16 formed in the channel member 15 and slidable on the platform 17 and type channel plate 18 is the column pusher 19, the type side contacting surface of which projects slightly beyond the corresponding surface of the member 15: this surface of the pusher, therefore, constitutes one side of the line channel and serves to contact with the type in the channel. The pusher 19 is provided with a stem 20 extending through the channel member 15 between the side bars of the lifter frame 2 and through the cross bar 14, terminating between the bar 14 and the bar 6 at which point the end of the stem is provided with an abutment 20' adapted to be engaged by the upper portion of the pusher lever 21, pivoted to the dependent lug 22 of the bracket 4 at the point 23 central of the lever. The lower end of the lever being pivotally connected with the rod 24 provided with a 130

spring box 25 intermediate of its ends said rod being operated in a well known manner by a cam surface on the disk M. The pusher 19 is also provided with a bolt 26 which 5 extends through the channel member 15 parallel with the stem 20, and the bolt is provided with an adjustable stop device 27 in the form of two bolt nuts.

A second cam surface on the disk M operates to depress a roller 28 mounted on one 10 end of the lever 29 pivoted intermediate its ends on the arbor 30 secured to the galley frame N; the other end of the lever projects beyond and to the right of the line channel 15 and is bifurcated, one of the bifurcations comprising a short leg 31 on which is pivotally mounted the line rule or gate operating rod 32. This rod rises vertically from the leg 31 and extends through an aperture 20 in the type channel plate 18 above which it is capped by an angle casting 33 extending around the end of the line pusher 19 and having secured to it in a well known manner the outer end of the rule 34. The rod 25 32 is cylindrical and the cap 33 is not secured to it; thus pivotal connection is provided. A coiled spring 35 (Fig. 2) surrounds a portion of the rod 32 and extends between the casting N and the end of lever 30 leg 31 so as normally to maintain the leg 31 and the end of the lever 29 to which it is attached, in lowermost position. In such, 35 normal, position the rule 34 extends above the left side of the channel in position to guide the left side of the type line during the raising of the latter by the lifter mechanism. The inner end of the rule is held against lateral movement but is free to move vertically in a groove in the rule guide block 40 35 secured to the usual movable channel block 36 and having a guide portion 35' extending over the type line channel. When the said channel block is adjusted in the usual manner to provide a channel entrance 45 suitable to the point size of the type being cast the block is also moved accordingly and with the latter the inner end of the rule, the pivotal connection of the cap 33 and the rod 32 at the outer end of the rule permitting 50 such movement of the rule. The outer end of the rule is then correspondingly adjusted by loosening the wing nut 37 and sliding the rule connection with respect to the angle casting 33.

55 The longer leg 38 of lever 29 has secured to it the lifter device operating rod 39 which is adjustable as to length and extends vertically through the supporting bracket 8 by which it is guided. The upper end of the 60 rod contacts with but is not fastened to the substantially horizontal arm of the bell crank lever 40 pivoted at 41 to the arms 42 of hub member 43 pivoted to the shaft 44 mounted in the vertical extensions 45 of the 65 side members of the lifter frame 2. The

substantially vertical arm of bell crank lever 40 normally extends as shown in Fig. 2 below the level of and at one side of the wiper plate 13 previously referred to. A spring 46 secured at one end to this vertical arm 70 and at its other end to brace 14 tends to hold the lever 40 in this normal position; a stop in the form of an abutment 47 extending laterally from the horizontal arm of the lever normally rests against the top surface 75 of one of the side members of the frame 2 against which it is held by said spring.

An adjustable setting device 48 shown in the form of a screw bolt mounted in an extension 49 on one of said arms 42 cams 80 against the seat 50 provided on the upper surface of one of the side arms of frame 2 and serves to adjust the relation between the frame 2 and the pivotal axis 41 of the bell crank lever 40 so that in raised position, as 85 will be explained hereinafter, the top of the platform 17 may be accurately alined with the level of the galley 1.

Arranged parallel with the spring 46 are the springs 51 and 52 the former connecting the brace 14 with the stem 20 of the column pusher 19 to maintain it in normal, retracted position and the latter spring 52 connecting the brace 14 with one of the arms 42 of the hub member 43 to normally maintain 90 the seat 50 of frame 2 against the stop device 48. The spring 52 is the dominant spring and keeps the stop 48 against the seat 50 at all times during the normal operation of the mechanism.

The galley 1 is supported on the top of the galley pan support 53 suitably secured above the cam disk M to the main galley frame N. The open end of the galley, which is near the line channel comes against the galley entrance plate 54 also secured to the frame N in such a manner that the upper surfaces of said plate 54 and the galley are at the same level. One side of the plate 54 forms the left wall of the line channel. A galley 105 bar 55 is adjusted in the usual manner to accommodate the galley to the length of line to be cast.

The usual line support 56 (Figs. 1 and 2) is moved along the line channel by the type 115 line when being formed or being moved to the platform 17 by the line hook. If the line is too long or too short for the measure set, the support 56 is moved in well known manner by the column pusher 19 when the latter 120 operates to discharge a line toward the galley and the said support 56 is thus caused to move the block 57 connected with an arm 58 of the extensible rock shaft 59; this shaft is thus rocked and moves a second arm 60 connected with said shaft and the slide rod 61 connecting the arm 60 with the trip device 62. The latter is of the well known kind found on type casting and composing machines of the species hereinbefore mentioned 130

and in connection with which the mechanism of the invention is herein disclosed: this trip device therefore requires no further description.

5 In the operation of the mechanism of the invention it will be assumed that the movable channel block 36 with the guide block 35 and the galley entrance plate 54 and also the rule 34 have been set in the usual way
10 to correspond with the point size of the type to be cast; also that the abnormal line trip device has been set for the length of line to be cast, the latter device by extending the rock shaft 59 and placing the arm 58
15 and block 57 to a position corresponding with the line length. It may also be assumed that the galley bar 55 has been secured with proper relation to the block 57 and the galley itself. When a number of
20 individual types have been cast sufficient to form a line and said types have been moved into the line channel between the fixed and movable channel blocks the cam disk M is caused in a well known manner, as by a
25 proper signal in the paper controller, to rotate a single revolution only, during which revolution the line is assembled and moved into the galley and the various mechanisms for accomplishing this purpose are then
30 caused to return to their normal positions as shown in Figs. 1, 2 and 5. The first function of the disk M is to operate lever L and cause the line hook K to draw the line of type from between the channel blocks
35 with their feet on the type channel plate 18 to a position between the column pusher 19 and the galley entrance plate 54 with their feet on the platform 17 of the channel member 15 of the type line lifter. The adjustment is such that the last type of the line just fully passes upon said platform and its rearmost vertical face against which the line hook contacts, is in accurate alinement with the inner surfaces of the rearmost rim
40 of the galley and of the rule guide block 35. The front vertical face of the foremost type of the line contacts with the line support 56 and if the line is of the proper length to correspond with the adjustment of the line trip device, said face alines with the inner surfaces of the galley bar 55 and the trip block 57.

The line having been so positioned the horizontal cam of the disk M depresses the 55 roller 28 of lever 29 and causes an upward movement of the rule operating rod 32 and the lifter device operating rod 39. Both rods move upwardly at the same time but the rod 39 moves faster than the rod 32 because its lever arm is greater. The upward travel of rod 32 moves the rule 34 upwardly until the upper position of the same shown in Fig. 3 has been reached. The movement of the rod 39 pushes the horizontal arm of the bell crank lever 40 and be-

cause the vertical arm thereof comes against the side of the wiper plate 13 the lever 40 cannot turn on its axis 41 but moves said axis and the lever 40 upwardly and, as is obvious, turns the lifter frame on its axis 3 70 and lifts the channel member 15 and the platform 17 with the line of type on it until the end of the vertical arm of the lever 40 reaches the upper surface of the wiper plate 13. During this movement the hub 43 and 75 arms 42 are held against rotation by the dominant spring 52. In this position the lifter frame has been moved on its axis 3 to its upper position in which the platform 17 is on a level with the galley floor and 80 the upper surface of the galley entrance 54. Further movement of the rod 39 will cause no further upward movement of the platform 17 and will result merely in the turning of the lever 40 on its axis 41 and the 85 wiping of the end of the vertical arm of the lever on the upper surface of the wiper plate 13. The spring 46 resisting the turning of the lever 40 is elongated during this wiping action. The stop 48 is adjusted so 90 that the extent of the lifting movement is reached when the platform is properly leveled in respect to the galley entrance 54.

While the lifter frame and the line of type on it are being raised the rule 34 is also 95 being raised, but more slowly so that it is still in contact with the line of type at the time the lifter frame has reached its uppermost position. Further movement of the lever 29 causes no effect upon the lifter 100 mechanism except the wiping of the lever 40 across the plate 13 but it causes the rule to rise until the limit of motion is reached at which point the rule will be free from contact with the type line and, as shown in Fig. 105 3, will be sufficiently above the type so that the line may be pushed toward the galley.

At this point the cam disk M moves the rod 24 and operates the lever 21 to force the type pusher stem 20 against the action of 110 its spring 51, and thus move the type pusher 19 to discharge the type line from the platform 17 to the galley entrance 54.

During the raising of the line the foremost type is always in contact with the line 115 support 56 and the rearmost type is first in contact with the line hook K and later with the guide block extension 35' overhanging the line channel and having, as has been hereinbefore stated, its inner side in alinement with the rearmost face of the last type of the line. The rear of the line is always held, therefore, during the lifting of the line, by the line hook or the guide block 35 or both. The forward face of the first 120 type is always supported by the usual line support 56 which, being slidale in the column pusher 19, is lifted with the type. Attention is directed to the fact that the line of type is guided not only on its ends as pointed 125 130

out and on its bottom by the platform 17, but also on its sides, one side being always in contact with the column pusher 19 and the other side being guided first by the galley 5 entrance plate 54 and then by the rule 34 or both the plate and the rule.

When upward movement of the line has commenced, this movement being arcuate because the lifter frame 2 is pivoted on the 10 axis 3, the effect is to tend to cause the types to lean against the type pusher 19 so that at the end of the motion, that is, when the line is ready to be discharged toward the galley, each individual type is tilted against the 15 column pusher and is therefore supported both by its foot on the platform 17 and by one of its sides on the pusher 19. This tilted position of the platform and wall, due to their arcuate travel from their normal sub- 20 stantially horizontal and vertical positions respectively, may cause the line to tilt before the discharge position has been reached particularly if the rise is considerable and the point size of the type is small. Practi- 25 cally, the jarring and vibration of the machine will cause the tilting of the type line in any case; and in this connection it may well be stated that machine vibration, ordinarily a bad influence, is helpful rather 30 than otherwise to provide a side and bottom support for the type line. The line therefore cannot become disrupted, as by vibration, at the time, particularly, that it is ready for discharge, at which time the rule 35 34 is of course in its uppermost position and the line is not guided on the galley side. Thus supported the line will remain on the lifter without danger of any of the types falling forward and subsequently being 40 lodged on their sides in the space between the line and the previous line standing on the galley entrance plate. The tilting of the lifter therefore forms an important feature of the construction to insure a perfect 45 elevation and discharge of the type line. The overhanging guide block 35' furthers this end also, as is obvious, by preventing the rearmost type of the line from toppling backward off the platform 17 into the line 50 channel.

To provide against breakage or straining of parts due to the possible failure of the lifter mechanism to rise—this may be due, it may be assumed, to a type lodging acci- 55 dentally between the platform 17 and the under side of the entrance plate 54—the bell crank 40 is pivoted to the yielding hub member 43 instead of to the lifter frame 2 itself. The operation in a case of this kind 60 is illustrated in Fig. 4. When the lifter device operating rod 39 pushes against the bell crank 40 and the frame cannot rise, the pivot 41 and the arm 42 of the hub member 43 will rise against the tension of spring 52, 65 and the hub member itself will be rocked on

its axis 44 until the lower arm of the bell crank 40 wipes across the plate 13. During this wiping action the hub member will not rock but the bell crank will rotate about its axis 41 against the action of its spring 46. 70 The spring 46 is weaker than the spring 52 and in any event is not strong enough to lift the frame 2. The accidental holding down of the lifter frame results in nothing more than the idle rocking of the hub member 43 75 and of the bell crank lever 40.

An adjusted limit of movement of the column pusher 19 is provided by the bolt 26 and its adjustable stop 27, the latter coming against the back of the channel 80 member 15 as a stop in the discharge motion. Further movement caused by the cam M merely compresses the spring box 25 in the rod 24.

The construction lends itself readily to 85 provide accessibility to the line channel as for cleaning purposes. The lifter device is moved upward by the operating rod 39 acting against the bell crank lever 40; this rod and this lever are not connected together 90 however and the device may at any time be lifted manually to the position, for example, shown in dotted lines in Fig. 3. When thus elevated the channel and the parts adjacent thereto may obviously be cleaned 95 and inspected without any difficulty whatever. The provision of separate operating rods for the rule 34 and the lifter mechanism with greater leverage for the latter makes it possible, while the lift of the rule 100 34 is always a constant, being slightly more than the overall height of the types, to obtain a line lift to any desired level, although, as will be obvious, the extent of the lift should be, as shown, as small as possible. 105 Furthermore, the independence of these mechanisms assures a proper proportioning and a proper strength for each, such as would not be possible if both the rule and the type line platform were both operated 110 by a single connection with the lever 29.

I claim—

1. A type casting and composing machine provided with means for casting types in selected sequence and conveying 115 them in the form of a line into a line channel, and in combination therewith, lifting mechanism including a platform and a wall, means for moving the type line upon said platform, means for operating the lifter 120 mechanism and tilting the platform and wall thereof, whereby at raised position both the foot and one of the sides of each type are supported upon the platform and the wall respectively, and the means for 125 discharging the type line from said lifter mechanism.

2. A type casting and composing machine for Semitic languages provided with means for casting types in selected sequence and 130

- conveying them in the form of a line into a line channel, and in combination therewith, a galley located on a level higher than that of the line channel, a line lifter having 5 a movable wall and a platform to support the feet of the types, means for moving the lifter in an arcuate path to tilt the types against said wall and to raise them to the level of the galley, supported both on their 10 feet by the platform and on one of their sides by the said wall, and means for subsequently moving said wall to push the type from the line lifter toward the galley.
3. In a type casting and composing machine 15 provided with means for casting types in selected sequence and conveying them in the form of a line into a line channel, and in combination therewith, means for adapting said machine to produce Semitic 20 composition, said last named means comprising a galley supported at a level higher than that of said line channel, a lifter mechanism provided with a platform for receiving a line of types and a line pusher, 25 means for operating said mechanism and causing the platform and pusher to tilt whereby at raised position the type line is tilted and both the platform and pusher serve to support the type line, and means for 30 operating the pusher to discharge the line into the galley.
4. A type casting and composing machine 35 provided with means for casting types in selected sequence and conveying them in the form of a line into a line channel, and in combination therewith, lifter mechanism including a platform for receiving a type line, a line rule, operating means for said mechanism comprising a cam, an intermediately 40 pivoted lever one end of which is acted upon by the cam, and a rod connecting the other end of the lever with the lifter mechanism, a rule operating rod connecting the rule with said lever at a point between its pivot and 45 the connection therewith of the lifter mechanism operating rod, whereby the rule and the lifter mechanism are operated by the said lever through independent connections therewith.
5. A type casting and composing machine 50 provided with means for casting types in selected sequence and conveying them in the form of a line into a line channel, and in combination therewith, line lifter mechanism 55 including a platform, a line hook for moving a line of type upon said platform and guiding the rear end of the line, a line support for guiding the front end of the line, means for operating the lifter mechanism, 60 a fixed galley guide having a portion extending over the line channel with the inner wall of said guide and its extension in alignment with the rear end of the line whereby the guiding of the rear end of the line is

transferred during the lifting action from the line hook to said guide extension, and means for discharging the line from the platform, the galley guide acting to guide the rear end of the line during said discharging action. 70

6. A type casting and composing machine provided with means for casting types in selected sequence and conveying them in the form of a line into a line channel, and in combination therewith, lifter mechanism 75 comprising a pivoted frame provided with a type line receiving platform, operating means for said mechanism comprising an operating rod the upper end of which is adapted to contact with said lifter mechanism to lift the frame on its pivot but is not secured to said mechanism, whereby the said frame is free to be lifted manually at any time for cleaning or other purposes, and means for discharging a type line from said 85 platform.

7. A type casting and composing machine provided with means for casting types in selected sequence and conveying them in the form of a line into a line channel, and in combination therewith, lifter mechanism 90 comprising a pivoted frame provided with a type line receiving platform, operating means for said mechanism comprising a cam actuated lever, a bell crank lever intermediately pivoted to said frame, a rod pivoted to said cam actuated lever and having its upper end in engagement with one arm of said bell crank lever, a fixed wiper plate with the side of which the other lower arm of said 100 bell crank lever contacts to prevent rotation of the lever and cause a lifting of the frame until the said lower arm reaches the top of the plate after which the bell crank lever may rotate with its lower arm wiping across 105 the top of the said plate, the frame meanwhile remaining stationary in raised position, and a spring tending to oppose the movement of the bell crank lever and to return it to normal position. 110

8. A type casting and composing machine provided with means for casting types in selected sequence and conveying them in the form of a line, into a line channel, and in combination therewith, lifter mechanism 115 comprising a pivoted frame provided with a type line receiving platform, operating means for said mechanism comprising a cam actuated lever, a hub member pivoted to said frame and having a radial arm, and an adjustable stop projecting from said arm to contact with said frame, a spring tending to maintain said stop against said frame, a bell crank lever intermediately pivoted to said arm, a rod pivoted to said cam actuated lever 120 and having its upper end in engagement with the horizontal arm of said bell crank, a fixed wiper plate with the side of which the lower 125

arm of said bell crank lever contacts to prevent rotation of the lever and cause a lifting of the frame until the said lower arm reaches the top of the plate after which the bell 5 crank lever may rotate with its lower arm wiping across the top of said plate, the frame meanwhile remaining stationary in

raised position, a second spring tending to oppose the movement of the bell crank lever and to return it to normal position, and a 10 stop on the horizontal arm of said bell crank lever to contact with said frame and limit the action of said second spring.

MAURITZ C. INDAHL.
